PERCOLATOR TOP

Nicholas B. Jagemann, Manitowoc, Wis., assignor
to Aluminum Goods Manufacturing Company,
Manitowoc, Wis., a corporation of New Jersey

Application August 9, 1951, Serial No. 16,219

Term of patent 14 years

(Cl. D44—26)

To all whom it may concern:

Be it known that I, Nicholas B. Jagemann, a citizen of the United States, residing at Manitowoc, in the county of Manitowoc and State of Wisconsin, have invented a new, original, and ornamental Design for a Percolator Top, of which the following is a specification, reference being made to the accompanying drawings, forming a part thereof:

In the drawings—

Figure 1 is a side elevational view of a percolator top showing my new design; and

Figure 2 is a top plan view thereof.

The characteristic features of the design reside in those portions shown in full lines.

I claim:

The ornamental design for a percolator top, substantially as shown and described.

NICHOLAS B. JAGEMANN.
